US00D761428S

(12) **United States Design Patent**
Birkenbach

(10) **Patent No.:** **US D761,428 S**
(45) **Date of Patent:** **** Jul. 12, 2016**

(54) **REFERENCE MARKER ARRAY**

(71) Applicant: **Brainlab AG**, Feldkirchen (DE)

(72) Inventor: **Rainer Birkenbach**, Erding (DE)

(73) Assignee: **Brainlab AG**, Feldkirchen (DE)

(**) Term: **14 Years**

(21) Appl. No.: **29/517,102**

(22) Filed: **Feb. 10, 2015**

(30) **Foreign Application Priority Data**

Aug. 14, 2014 (EM) 002519405
